UNITED STATES PATENT OFFICE.

HENRY W. BEESTON, OF PHILADELPHIA, PENNSYLVANIA.

DESIGN FOR AN UMBRELLA-STAND.

SPECIFICATION forming part of Design No. 19,408, dated November 12, 1889.

Application filed September 26, 1889. Serial No. 325,177. Term of patent 8½ years.

To all whom it may concern:

Be it known that I, HENRY W. BEESTON, a citizen of the United States, residing at Philadelphia, in the county of Philadelphia and State of Pennsylvania, have invented and produced a new and original Design for Umbrella-Stands, of which the following is a specification, reference being had to the accompanying drawing, forming part thereof.

10 My invention has relation to umbrella stands or receptacles for holding umbrellas, canes, and the like; and it consists of a new and original design for such articles which will present a highly ornamental and attractive appearance, the main portion or body of such stand being of cylindrical shape, with a suitable base or bottom and a top, the main portion or body of such stands between said top and bottom having or being provided with

15 ribs or ridges extending diagonally from side to side, of equal distance apart, and intersecting or forming junctions with similar ridges extending from side to side, but in opposite directions from the first-mentioned ridges, the result being in effect a "criss-cross." The

20 spaces between these ridges are of substantially diamond shape, and are slightly depressed or concaved, so that if viewed in cross-

25

section between one set of ribs and through the other set the appearance would be wave-like or undulatory.

In the drawing, A represents the main portion or body; a, the ribs or ridges running in one direction, and a' the crossing or ribs running in the other direction.

a² represents the intervening depressions or concavities.

B represents the flaring base or bottom, provided with round moldings b, and C the flaring top or dome, said base and top being secured to the body A at b' and c, respectively.

Having fully described my design, what I claim as new, and desire to secure by Letters Patent, is—

The design for umbrella-stands, consisting of the cylindrical body portion A, provided with a top and base and having the ridges a a', with the intervening depressions a², substantially as shown and described.

In testimony that I claim the foregoing I have hereunto set my hand this 24th day of September, A. D. 1889.

HENRY W. BEESTON.
